UNITED STATES PATENT OFFICE

ERNEST RICHARD STANDFUSS, OF MILWAUKEE, WISCONSIN, ASSIGNOR TO HARNISCH-
FEGER CORPORATION, OF MILWAUKEE, WISCONSIN, A CORPORATION OF WISCONSIN

EXCAVATOR TOOTH

Application filed November 25, 1937. Serial No. 235,453.

This invention relates to teeth for use with excavating equipment such as dragline buckets, scoops, dippers, power shovels, power hoes and various other similar and diverse excavating machines and implements.

One of the objects of the present invention is to provide such an excavating tooth of the type having a removable point and wherein the point is rigidly and securely held in proper position and yet may be readily and easily removed and reversed or renewed.

Another object is to provide a tooth of this character having improved means for releasably interlocking the point with the body of the tooth.

Other objects and advantages reside in certain features of the construction, arrangement and combination of parts which will be hereinafter more fully described and particularly pointed out in the appended claims, reference being had to the accompanying drawings forming a part of this specification, and in which:

Figure 1 is a view partly in central longitudinal vertical section and partly in side elevation showing an excavating tooth embodying the present invention;

Figure 2 is a top plan view of the tooth shown in Figure 1;

Figure 3 is a fragmentary bottom plan view of a portion of the tooth shown in Figures 1 and 2;

Figure 4 is a detail view in elevation showing how one of the wedge keys is constructed; and

Figure 5 is a view in horizontal section on line 5—5 of Figure 1.

Referring to the drawings, it will be seen that the excavating tooth embodying the present invention comprises a body 1 having attaching portions 2 and 3 adapted to be riveted or otherwise securely fastened to the bucket, dipper, scoop, shovel, or other implement on which the tooth is used. The body 1 is provided with an integral forwardly and downwardly extending shank 4. A point 5 is provided and has a socket 6 in which the shank 4 is fitted. The shank

4 and the point 5 are provided with transverse openings 7 and 8, the opening 8 of the point intersecting the socket 6 thereof. In the assembly, these openings 7 and 8 are in substantial registration or substantial alignment. The shank 4 and the socket 6 are of non-circular cross section and are correspondingly formed and tapered so that as the shank 4 is forced into the socket, the shank and point are rigidly connected and cannot turn relative to each other.

For the purpose of forcing the shank into the socket or rather of forcing the point up on the shank to cause the shank to be tightly interfitted with the socket, cooperable wedge keys 10 and 11 are provided and are extended through the openings 7 and 8, the key 10 having a rounded surface engaged with a rounded end wall of the opening 8 in the point and the key 11 having a similar surface engaged with a similar end wall of the opening 7 in the shank. The keys 10 and 11 are oppositely tapered and have correspondingly inclined surfaces 10^a and 11^a engaged with each other. For holding the key 10 fixed against movement axially or lengthwise through the openings 7 and 8, a lug 12 is formed integral with the key 10 and extends laterally therefrom and into a pocket 13 formed in the shank 4 and communicating with the opening 7 thereof. The opening 13 is made sufficiently deep to permit the key 10 to follow the point 5 up along the shank 4.

In assembling the point with the shank of the tooth, the point is positioned on the tooth, that is, the shank 4 is fitted in the socket 6 of the point. This brings the openings 7 and 8 into substantial alignment and permits of the insertion of the key 10 into the openings 7 and 8, the lug 12 of the key being entered into the pocket 13. The key 11 is then introduced into the openings 7 and 8 and engages the key 10. A hammer or any other suitable means is employed for driving the key 11 in as far as may be necessary to tightly wedge the keys in position and to force the point up on the shank 4 until the shank 4 has binding engagement with the point. To provide for the releas-

ably locking of the key 11 and consequently of the key 10 in the assembly, the lower end of the key 11 is provided with a lengthwise slot or split 15 defining securing wings 16 and 17, the wing 16 being cut off to facilitate spreading of the wings by a hammer or any other suitable tool. The metal of the key 11 is sufficiently bendable to permit the wings 16 and 17 to be bent over laterally from the full line position shown in Figure 4 to the dotted line position shown in the same figure. When the wings 16 and 17 are thus spread they are received in a recess 20 provided in the point 5 around each end of the opening 8.

With this construction the point is locked absolutely rigid on the shank and it remains so locked even under the severe usages of actual working conditions. The outer extremity of the point 5 should be shaped as indicated in full lines in Figure 1 but under the wearing action of actual use it gradually wears away as indicated by the dotted lines. When thus worn away the tooth must be reversed to present the proper edge at the outer extremity thereof. This may be accomplished by bending the wings 16 and 17 back to the full line position shown in Figure 4 driving out the wedge 11 and removing the wedge 10. The point 5 may then be easily forced off of the shank 4, after which it is reversed and put back on the shank. The keys 10 and 11 are then replaced although a new key 11 may be used if the wings 16 and 17 are in any way damaged. With this construction, the points may be used over and over again and yet are always firmly and securely and rigidly connected and mounted on the shank of the body of the tooth.

The invention claimed is:

1. A tooth for use with excavating equipment including a body provided with a shank, a point, said point and said shank being interfitted and having transverse openings, cooperable wedging keys fitted in said openings, one of said keys having a laterally extending lug, the shank having a pocket receiving said lug, and means for releasably locking the other key in position.

2. A tooth for use with excavating equipment including a body provided with a shank, a point, said point and said shank being interfitted and having transverse openings, cooperable wedging keys fitted in said openings, means for fixing one of the keys against lengthwise movement through the openings, the other key having one end split to provide bendable securing wings engageable with the point for fastening the key in position.

3. A tooth for use with excavating equipment including a body provided with a shank, a point having a socket in which the shank is snugly fitted, said shank having a

transverse opening, said point having an opening intersecting the socket thereof and adapted to be alined with the opening in the shank, cooperable keys extending through said openings and engaging the point and shank respectively, one of the keys having means cooperable with the shank for holding it against lengthwise movement through the openings, and means for releasably locking the other key in position.

4. A tooth for use with excavating equipment including a body provided with a shank, a removable and reversible point having a socket receiving the shank, said point and said shank having openings, cooperable keys fitted in the openings and engaging the point and shank respectively, and means for fixing one of the keys against lengthwise movement through the openings, the other key having one end split to provide securing wings engageable with the shank for fastening the keys in position.

5. A tooth for use with excavating equipment including a body provided with a shank, a removable and reversible point having a socket receiving the shank, said point and said shank having openings, cooperable keys fitted in the openings and engaging the point and shank respectively, and means for fixing one of the keys against lengthwise movement through the openings, the other key having one end split to provide securing wings engageable with the shank for fastening the keys in position, the point having recesses receiving the wings in either position of the point.

6. A tooth for use with excavating equipment including a body, a point associated with the body, said body and said point having substantially alined openings, a pair of cooperable oppositely tapered keys extending through said openings, one of said keys and said body having cooperating means for holding such key against lengthwise movement while permitting it to move laterally under the influence of the other key, and means for releasably locking the other key in position.

7. A tooth for use with excavating equipment including a body, a removable point associated with the body, said body and said point having substantially alined openings, a pair of cooperable oppositely tapered wedging keys extending through said openings and operating to secure the point rigidly to the body, and bendable securing wings on one of the keys for releasably locking it in position.

8. A tooth for use with excavating equipment including a body provided with a shank, a removable point having a socket receiving the shank, said point and said shank having transverse openings, cooperable wedging keys fitted in said openings

and engaging the point and shank respectively, a laterally extending lug formed on one of said keys and engaging a part of the tooth fixed against transverse movement to hold its key against lengthwise movement through the openings and means carried by the other key for releasably locking the other key in position.

In witness whereof, I hereto affix my signature.
